UNITED STATES PATENT OFFICE.

JOHN K. WILLIAMS, OF AKRON, OHIO.

RUBBER-TIRE-SETTING MACHINE.

SPECIFICATION forming part of Letters Patent No. 697,056, dated April 8, 1902.

Application filed October 14, 1901. Serial No. 78,624. (No model.)

To all whom it may concern:

Be it known that I, JOHN K. WILLIAMS, a citizen of the United States, residing at Akron, in the county of Summit and State of Ohio, have invented a certain new and useful Improvement in Rubber-Tire-Setting Machines, of which the following is a specification.

My invention has relation to improvements in machines for placing or "setting" solid rubber vehicle-tires in channeled metallic tires.

The object of my invention is to produce a new and improved machine of the class named in which the line of draft of the wires shall be between the clamping-arms and which shall be simple in construction, efficient in operation, and in which the number of parts shall be reduced to a minimum.

To the aforesaid object my invention consists in the peculiar and novel construction, arrangement, and combination of parts hereinafter described, and then specifically pointed out in the claims, reference being had to the accompanying drawings, forming a part of this specification.

In the accompanying drawings, in which similar reference-numerals indicate like parts in the different figures, Figure 1 is a front elevation; Fig. 2, a section at the line *x*; Fig. 3, a section at the line *y*; Fig. 4, a rear elevation; Fig. 5, a section at the line *z*, and Fig. 6 a view of the winding-crank and pinion.

Referring to the figures, 1 is a metallic casting of the general form shown, being a plate 35 with a lateral extension to permit of its being bolted for support to a post 2. In the lower edge is an upwardly-extended curved notch 3, for a purpose to be stated, from one side of which depends an arm 4, from the front face 40 of which extends an integral horizontal foot 5, having near its outer end a screw-threaded opening in which runs a screw 6, provided at its lower end with a hand-wheel 7, by which it may be turned, and at the top a freely-mounted cap 8, having a curved top to adjustably support a wheel-felly 9 during the process of setting the rubber tire.

The cap 8 has a rearwardly-projecting blade 10, the outer end of which runs freely in a vertical channel 11 in the arm 4, and thus holds the cap against turning with the screw.

In the lower front face of the plate 1, on op-

posite sides of the notch 3, are pivots 12 13, screw-threaded at the outer ends, on which are freely mounted the wire-clamps 14, between which extends a connecting-bar 15, the ends of which are perforated and fit on the pivots 12 13 and are retained by the nuts 16 17.

Each wire-clamp consists of an inner bar 18, that rests against the plate 1, and an outer jaw 19, having pivotally mounted in a notch in its upper end a handle-cam 20, arranged to bear against the bar 18 and when the handle of the cam is rocked down to force the lower end of the jaw 19 toward the lower end of the bar 18.

Between the lower ends of the bar 18 and jaw 19 and supported by the pivot 12 or 13 is an intermediate plate 21 of like width.

The outer lower ends of the bar 18 and jaw 19 are reduced toward their inner faces, and the adjacent faces of these parts and the plate have corresponding oppositely-disposed grooves to grasp the tire-wires.

To the upper ends of each of the bars 18 is pivotally connected one end of a flat link bar 22, their opposite ends being freely mounted on a screw 23, having a hand-wheel which passes through a slot 24 in the plate 1 and enters a nut 25 at the back of the plate 1.

By raising or lowering the screw 23 in the slot 24 the wire-clamps can be brought perpendicular to the tangent of the wheel-rim and locked at any desired point, thus adapting the machine to wheels of different diameter.

Through the plate 1 are bored two holes to receive winding-shafts 26 27, having bosses at each end.

Back of the plate 1 on the shafts 26 27 are splined-like gear-wheels 28 29, respectively, provided with pawls 30 31, respectively. The shafts 26 27 are free to slide lengthwise in their openings and are held until it is desired to draw them backward by a plate 32, retained to the pivot-shaft of the pawl 29 by a set-screw 33.

In the front end of each shaft 26 27 is a notch like those in a screw-head, in which to place the wires for winding.

In the back of the plate 1 are three like socket-holes, the upper and lower, 34 and 35, respectively, shown in Fig. 4, the central one being obscured by the pinion. Each hole has

bosses at the rear of the plate to give additional bearing length, similar to those about the holes for the shafts 26 27. A shaft 36 is fitted to accurately enter these holes and has 5 at its outer end a crank arm and handle and bears a pinion 37, adapted to mesh in the gears 28 29.

In operation the rubber tire 38, with the wires 39 40 inclosed, is placed about the wheel 10 in the channeled metallic tire and secured at one end in the right wire-clamp 14. The opposite ends of the wires are then brought between the members of the left wire-clamp 14 and the end of one, 39, placed in the notch in the shaft 27, and the other is brought under the shaft 27 and up into the notch in the shaft 26. The crank-shaft is then placed in one of the holes 34 35, and for the purpose of illustration it will be assumed in 34, and the 15 wheel 28 and shaft 26 turned, winding the wire 40 on the front end of the shaft until it is tight. The operation is then repeated with the wheel 29 until the wire 39 is drawn correspondingly tight by the shaft 27, the gears 28 29 being held by the pawls 30 31. The 20 crank-shaft 36 is then placed in the intermediate socket-hole, with the pinion 37 meshing in both gears 28 29 and turned simultaneously, winding the wires on both shafts 26 27 until 25 the required tension is secured. In this operation the wire coils close to the boss on the face of the plate 1 in a spiral, forcing or drawing the shaft on which it is winding to the front, and thus always causing the wire to 30 draw in the same relative position. The left wire-clamp 14 is then tightened on the wires and the wires cut between the clamps 14 at suitable distances for forming a joint, the notch 3 permitting a file or like tool to pass 35 for that purpose. The shafts 26 27 are then pushed into the plate 1 until their ends are flush with the face of the bosses, thus removing them out of the way of the workman in making the joint and stripping the coiled wire off from the shafts. The ends of the 40 wires are then brazed together, the clamps 14 released, and the wheel removed to have the ends of the rubber brought together in any 45 approved manner.

50 Having thus described my invention, what I claim, and desire to secure by Letters Patent, is—

1. In a machine for placing rubber tires on vehicle-wheels the combination of means to hold one end of the wires, means for holding back the rubber on the other end of said wires and means situated intermediate of said previously-mentioned means for drawing said wires taut.

60 2. The combination of two clamping-arms arranged substantially radial to the wheel to be fitted and means for drawing said wires taut situated intermediate said clamping-arms.

65 3. In a machine for placing rubber tires on vehicle-wheels consisting of a clamping-arm to hold one end of said wires, a second clamp-

ing-arm adapted when so desired to clamp said wires, a tightening device situated between said clamping-arms, substantially as 70 shown and described.

4. The combination in a machine for placing rubber tires on vehicle-wheels consisting of two clamping-arms arranged substantially radial to the axis thereof, two separate tightening means situated between said clamping-arms to draw said wires taut independently of each other, substantially as shown and described.

5. The combination in a machine for placing rubber tires on vehicle-wheels consisting of two clamping-arms arranged substantially radial to the axis of said wheel and two tightening devices situated intermediate of said clamping-arms to be operated either singly 85 or in conjunction with each other as desired, substantially as shown and described.

6. The combination in a machine for placing rubber tires on vehicle-wheels consisting of two clamping-arms arranged substantially 90 radial to the axis of the wheel, means as a U-shaped cap for supporting said wheel during said operation, a guide attached to said U-shaped cap to retain said cap constantly in one direction and means as winding-shafts 95 situated intermediate said clamping-arms to tighten said wires, substantially as shown and described.

7. The combination in a machine for placing rubber tires on vehicle-wheels consisting 100 of a pair of clamping-arms pivoted on bolts attached to the housing arranged to form fulcrums for said clamping-arms and means situated between said clamping-arms to draw said wires taut, substantially as shown and 105 described.

8. The combination in a machine for placing rubber tires on vehicle-wheels consisting of a housing, vertical slot in said housing, a vertically, sliding clamping device traveling 110 in said slot, a pair of levers attached to said clamping device at one end severally attached to the upper end of rocking clamping-jaws arranged to grip the wires in placing said 115 tires constructed to be placed radial to said wheel-axis by the vertical motion of said clamping device and said slot, substantially as shown and described.

9. The combination in a machine for placing rubber tires on vehicle-wheels consisting 120 of a housing to support said device and an adjustable clamping device attached to travel in a vertical slot in said housing and adjust the position of two clamping-arms, two clamping-arms adapted to grasp the wires used in 125 placing said tire, and means as winding-shafts to draw said wires situated between said clamping-arms, substantially as shown and described.

10. The combination in a machine for placing rubber tires on vehicle-wheels consisting 130 of two clamping-jaws radially adjustable, means as two winding-shafts situated in the housing supporting said clamping-jaws and

- means adapted to revolve said winding-shafts in unison or separately, substantially as shown and described.
11. In a machine for placing rubber tires on vehicle-wheels consisting of a housing suitably supported, a pair of winding-shafts situated in said housing intermediate said clamping-jaws and means to revolve said winding-shafts independently or in unison, as desired, substantially as shown and described.
12. In a machine for placing rubber tires on vehicle-wheels consisting of a housing suitably supported, two clamping-jaws mounted thereon and capable of radial adjustment, means as two winding-drums situated between said clamping-jaws to tighten said wires used in placing said tires and means as a crank-shaft bearing a tight pinion-gear to rotate said winding-shafts either independently or in unison, substantially as shown and described.
13. In a machine for placing rubber tires on vehicle-wheels consisting of a housing suitably supported, a pair of clamping-jaws radially adjustable, a pair of winding-shafts to tighten the wires used in placing said tire, a slot in the end of said shafts to start the rotation of said wires and permit their free removal therefrom, means such substantially as shown for rotating said winding-shafts either independently or in unison.
14. In a machine for placing rubber tires on vehicle-wheels consisting of a housing suitably supported, clamping-jaws radially adjustable mounted thereon, a pair of winding-shafts situated between said clamping-arms capable of longitudinal movement as the number of coils of wires thereon renders the same necessary and means for causing the revolution of said winding-shafts to rotate 40 independently or in unison, substantially as shown and described.
15. In a machine for placing rubber tires on vehicle-wheels consisting of a housing suitably supported, a pair of clamping-arms mounted thereon radially adjustable, a pair of winding-drums situated between said clamping-arms arranged to draw taut the wires used in placing said tires, means as gear-wheels mounted on said winding-shafts 45 to rotate said shafts, a pair of rocking pawls mounted on said housing adapted to permit the rotation of said gear-wheels and shafts in one direction and prevent it in the opposite direction, and means such substantially as shown for rotating said gears and shafts independently or in unison, substantially as 50 shown and described.
16. The combination in a machine for placing rubber tires on vehicle-wheels consisting of a housing suitably supported, a pair of clamping-jaws mounted thereon radially adjusted, a pair of winding-shafts situated between said clamping-jaws, gear-wheels mounted on said winding-shafts to control the 55 rotation thereof, said winding-shafts being capable of longitudinal motion, a plate mounted on a pin on said housing to retain said gears on said winding-shafts and means to rotate said gears independently of each other or in 60 unison, substantially as shown and described.
- In testimony that I claim the above I hereunto set my hand in the presence of two subscribing witnesses.
- JOHN K. WILLIAMS.
